OTHO FULTON, OF BROMLEY, ENGLAND

APPARATUS FOR PICTURE TRANSMISSION OR THE LIKE

Application filed March 16, 1929, Serial No. 347,623, and in Austria August 22, 1928.

This invention is concerned with improvements in or relating to methods of and apparatus for picture transmission, television or the like.

5 In known systems for the transmission of pictures or the like employing a receiver of the kind comprising a recording apparatus that is not properly responsive to picture signals varying in amplitude according to 55
10 the light and shade of the transmitted picture, the reproduction of half tones pictures cannot be obtained without the introduction of complicated measures including the use of screens. For example, a simple receiver 60
15 operating in the well known manner by electro-chemical reaction is not properly responsive to such varying picture signals.

An object of the invention is to provide a 20 method of transmitting pictures or the like, and apparatus therefor by means of which a picture can be transmitted in such a manner as to be reproduced by the receiver of the aforesaid kind as a half-tone reproduction.

25 The present invention comprises a method of picture transmission, television or the like employing a receiver of the kind aforesaid wherein the energy fluctuations produced or controlled by an exploring device 70 (e. g. a light sensitive cell) and varying in amplitude in accordance with the light and shade of the picture, are translated into signal impulses of differing time duration according to the nature of the picture.

30 The invention also comprises a method as aforesaid wherein the energy fluctuations are applied to an electrical system which is periodically reduced to a neutral state and 75 is brought to an active state by the energy fluctuations for a greater or lesser time interval according to the nature of the picture.

35 The method of this invention may be carried out by charging an electric condenser at 80 uniform intervals and controlling the discharge of the condenser by means of the energy fluctuations aforesaid to produce signal impulses of differing time duration according to the variations of amplitude of 85 the energy fluctuations.

Thus by exploring the picture to be transmitted with a device such as a photo-electric-cell which is influenced for example as regards its electrical resistance in proportion to the light beam directed upon it and 55 using the device as a discharge path for the condenser, the discharge period will vary in duration according to the intensity of the light upon the photo-electric-cell. By applying the potential variations produced at 60 the condenser to the control electrode of a thermionic valve, impulses can be obtained which have a duration depending upon the time of discharge. The condenser is charged at uniform intervals so that a succession of signal impulses is obtained. 65

The invention will now be more particularly described with reference to the accompanying drawing, in which:

Figure 1 is a diagrammatic representation of means for carrying out the invention; 70

Figure 2 shows diagrammatically an arrangement of apparatus in a practical form; 75

Figure 3 shows explanatory charge and discharge curves.

Referring to Figure 1 a photo-electric cell 11 is connected across the grid and cathode of a three electrode thermionic valve 80 12 and to the grid of the valve there is also connected a brush 13 bearing upon a rotary switch member 14 having contacts which are connected to the negative terminal of a battery 15 the positive terminal of which is 85 connected to the cathode of the valve.

The switch member 14 is rotated and the grid of the valve 12 and one element of the cell 11 will consequently be given a negative charge from the battery 15 at regular intervals, namely, when a contact of the switch member 14 passes beneath the brush 13. 90

The picture to be transmitted is explored by a beam of light directed from the picture on to the cell 11 and this beam therefore varies in brightness according to the light and shade of the picture. When there is substantially no light directed onto the cell corresponding to a very dark part of the picture no current will flow in the anode 100

circuit of the valve 12 owing to the negative charge upon the grid thereof.

When a bright beam of light is directed upon the cell corresponding to a light part 5 of the picture the cell will become conductive so that the negative charge upon the grid rapidly leaks away through the cell and a current will flow in the anode circuit of the valve.

- 10 By suitable selection of the electrical values of the several components the apparatus can be adjusted in such manner that when no light is directed upon the cell voltage from the grid will not rise sufficiently to enable a current to appear in the anode circuit of the valve (or the anode current to be increased) within the interval 15 between two successive negative charges obtained through the switch 13, 14. Thus, as 20 the resistance of the cell will be decreased in proportion to the light upon it the current impulses obtained in the anode circuit of the valve are proportional as regards their duration to the brightness of the light 25 upon the cell.

In Figure 3 the time intervals are plotted along the line 20, 21, the grid potentials along the line 20, 22, and 23, 24 represent the grid potential at which the valve becomes conductive. The intervals between the negative charges upon the grid are indicated by 125.

If it is assumed that the voltage upon the grid on being charged immediately reaches the value indicated at 20 the subsequent discharge which takes place through the cell in accordance with the general known exponential function is represented by the curve such as 26, and this is repeated 35 for each charge. The shape of the curve depends upon the brightness of the light beam that is directed upon the cell 11, that is to say upon the resistance through which the charge leaks away. In Figure 3 several typical curves are shown for the rise 40 of the potential on the grid for different resistance values assumed by the cell. Thus the curve 25 may represent an intense illumination of the cell. The curve 27 corresponds to a less bright illumination and 45 the curve 28 for no illumination shows the voltage rising insufficiently to cause a current to appear in the anode circuit of the valve.

50 Therefore, assuming an illumination of the cell corresponding to the curve 26, impulses are obtained which have the form of the shaded portions in Figure 3 which vary in duration according to the brightness 55 of the picture being explored. These signal impulses will be produced with uniform time intervals depending upon the frequency of charging the grid of the valve.

Referring to Figure 2, there is shown 60 additional apparatus for the practical

working of the invention. There is provided a variable condenser 30 shunted across the cell 11 to provide for adjustment of the capacity to be charged. A battery 31 is provided mainly to increase the sensitivity of the cell 11 and a resistance 32 is employed in the charging circuit which has the effect of prolonging the charging of the condenser as represented by the curve 29 in Figure 3. It is found that this ensures a smooth and pleasing appearance of the reproduced picture.

Although the charging of the light sensitive cell and associated parts at uniform intervals is effected in the example described by means of a rotary switch which may for example be self excited or driven in any suitable manner, any other means may be employed for supplying the charging potentials such as purely electrical means.

The interval of time between successive charges is preferably chosen in such a manner that having regard for the circumferential speed of the transmitting or receiving drum the reproduced picture has a screen effect which is of the same order as that usually employed in printing. By adjusting the frequency of charging and by a proper selection of the electrical values of the apparatus employed it is possible to obtain any desired degree of fineness and by suitable adjustment the gradation of the picture can be influenced in order to flatten or intensify the reproduction of a picture that is not very suitable as regards contrasting values.

I claim:

1. In a communication system, a three-electrode valve having a grid and a cathode, a condenser connected in circuit with said grid and cathode, means for periodically charging the condenser to interrupt the flow of current from said valve, and a photocell connected to the grid to provide a leak path whereby the period of interruption of the flow of current from the valve is inversely proportional to the intensity of the illumination impinging upon said cell.

2. In a communication system, the combination with a three-electrode valve having an anode, a grid, and a cathode, a photocell connected to said grid to provide a leak path, and means for periodically charging said grid to preclude the flow of current from said anode until the grid charge leaks off through said path.

In testimony whereof I affix my signature.

OTHO FULTON.
